UNITED STATES PATENT OFFICE.

JOHN W. FREE, OF WOODLAWN, PENNSYLVANIA.

SHEET-METAL CONVEYER.

Application filed October 4, 1923. Serial No. 666,546.

To all whom it may concern:

Be it known that I, JOHN W. FREE, residing at Woodlawn, in the county of Beaver and State of Pennsylvania, a citizen of the 5 United States, have invented or discovered certain new and useful Improvements in Sheet-Metal Conveyers, of which improvements the following is a specification.

My invention relates to improvements in 10 apparatus for conveying sheet material, and consists in improvements applicable to the mechanism which constitutes the subject-matter of Letters Patent of the United States, No. 1,482,921, granted me February 15, 1924. This mechanism is developed specifically as feed-mechanism, for feeding steel sheets one by one to a tin pot, in the course of producing what is known commercially as tin plate.

20 In the prior patent named, mechanism is described for raising the sheets one by one from a pack which stands on edge, immersed in water, in a bosh and for transferring the sheets over a suitable guideway and for 25 plunging them beneath the bath of molten tin in the tin pot. The specification of that prior patent explains that the individual sheet raised upwardly from the pack is carried edgewise over the curved surface of the 30 guideway. The curvature of the guideway is described to be advantageous, in that the bending of the sheet upon it tends to free from it a second sheet, if by chance a second sheet adhering to it should be raised with it 35 from the pack. The specification further explains that the surface of the rising sheet is exposed, and may be tapped with a hammer, and so a persistent adhesion between sheets may be broken, without disturbance 40 of the normal operation of the machine.

In a second application, filed February 2, 1923, Serial No. 616,518, I have described and claimed an accessory appliance which, cooperating with the apparatus which constitutes the subject-matter of the patent first-named, tends additionally to break adhesions between sheets, before the lifting of the sheet from the bosh begins. My present invention concerns accessory appliances, 50 adapted to cooperate with the apparatus of my patent first-named, and tending additionally to break adhesions between sheets forming a double, after the sheets have been raised from the bosh and are advancing over the guideway. The appliances which constitute my present invention may if desired be

used conjointly with those of my second application, Serial No. 616,518.

In the accompanying drawings Fig. I is a view in side elevation of so much of the 60 tin-pot feeding apparatus as is necessary to afford understanding of my present invention, and in this figure the accessory apparatus in which my present invention is found, appears in organized assembly with the 65 other parts. Fig. II is a view in front elevation of the same assembly. The line of view of Fig. II is indicated by an arrow II, Fig. I.

In these drawings the tin pot is not shown, 70 but it will be understood to be situated at the extreme left, Fig. I, and arranged to receive the sheets as they advance one by one downward over the left-hand slope of the guideway.

75 2 is the bosh filled with water, in which the freshly pickled sheets are introduced, and where they rest upon edge in a pack S which stands in approximately vertical position. The position is, however, not exactly 80 vertical, the sheets incline somewhat, in a direction away from the tin pot. The plane in which the sheet lies in the pack S is in this instance parallel to the line upon which the sheet ultimately enters the bath of tin 85 in the tin pot.

Between the bosh 2 and the tin pot extend the upwardly arched approximately semi-circular ways 11, over which the sheets are carried one by one from the bosh to the tin 90 pot. The downward slope (the left-hand slope, Fig. I) of these ways is magnetized, to the end that the descending sheet shall not fall, but, pushed from behind, shall advance under control and be plunged gradually and at a properly controlled and uniform speed beneath the bath of molten metal 95 in the tin pot.

100 Means for disengaging from the pack S the top-most sheet, and for raising it and dragging it upon the upward slope of ways 11 are found in a bell-crank lever 15. This lever is fulcrumed upon the free end of a beam 14 which at its remote end is pivoted in a fixed support. The bell-crank lever 15 105 is linked also to the rotatable power shaft 3. The range of swing of beam 14 is fixed within narrow limits. The work-arm of bell-crank lever 15 is extensible and contractible, telescopically, and is at its free end 110 equipped with suction cups. When both beam 14 and bell-crank lever 15 have turned

- to the limit of their ranges clockwise, as seen in Fig. I, and when the work-arm of the bell-crank lever, being then downwardly and outwardly inclined, has extended and has 5 suctionally engaged the outermost sheet of pack S, the continued rotation of shaft 3 is effective, first to swing beam 14 anti-clockwise, and to cause the work-arm of the bell-crank lever (now extended) to recede 10 in right-to-left direction, carrying with it the suctionally engaged sheet. As soon as beam 14 has reached the limit of its swing, continued turning of shaft 3 causes bell-crank lever 15 to turn anti-clockwise on its 15 fulcrum, and in so doing to raise the engaged sheet edgewise and to drag it upward over ways 11. All these matters are fully described in the first of my prior applications mentioned above.
- 20 Cams 46 may be provided (not shown in my first application) whereby suction may be exerted upon the sheet as the cups engage it, and a stop 47 may be provided, for relieving the vacuum within the cups 25 as the lever 15 approaches the limit of its range of upward movement. These features will be understood without further elaboration, and they are incidental to the elucidation of my present invention. Suffice it to 30 repeat that the cup-equipped lever engages the top most sheet of the pack, swings it aside from the pack, then lifts it edgewise and drags it along ways 11, until it is engaged by other instrumentalities. Then 35 the suction is broken and the lever 15, free of the sheet just carried, swings down again, to engage a new sheet.
- Coming now to the particular features in which my present invention resides, I call attention, first, to the disk or roller 48. It is 40 idly mounted on an axis parallel to the axis of curvature of ways 11 and to the pathway of sheet advance. It is placed at a carefully determined interval from ways 11, and, as appears in Fig. I, approximately midway of 45 the quadrant to which the rising right-hand portion of the ways 11 is shaped. The disk is arranged to be engaged by the outer surface of a double (that is to say, two 50 sheets accidentally adhering together) borne by the rising bell-crank lever 15, and to exert immediately upon the outer and undesired member of the double a frictional drag upon its advance,—a yielding 55 resistance to advance. To this end the disk is, as has been said, idly-mounted, and is formed of elastic material, conveniently of rubber. The function of the disk is to exert a drag, insufficient to disturb normal 60 operation, but, in case of adhesion and the accidental raising of a double (the friction of the roll being greater upon the double thickness than upon the normal single sheet), the friction will tend to break 65 the adhesion, and allow the released sheet to fall back again by gravity and to resume its position with respect to stack S, ready to be transferred in proper time, with the next swing of lever 15.
- A pipe 49 extends athwart the path of 70 the sheets upon ways 11. It is supplied with compressed air, and delivers compressed air in jets through orifices 50 formed at suitable intervals throughout its length. The jets blow upon the surface of 75 the advancing sheet and strip away from the upper surface of the sheet much of the water which otherwise would be carried over to the tin pot.
- At a suitable point in the extent of arched 80 guide ways 11, and preferably as shown near the crown of the arch, is arranged a magnetic roller 51. It is mounted upon an axis parallel to the axis of curvature of 85 ways 11 and to the pathway of sheet advance, and it is positively driven, as by a sprocket drive 52, and at a surface speed which is different from and which preferably exceeds somewhat the speed at which 90 the sheets are carried normally over ways 11. The roller 51 is arranged at such an interval from ways 11 that, in case of adhesion, adhering sheets borne by bell-crank lever 15 will pass beneath it, but that its magnetic effect and if desired the friction 95 of its contact will be exerted upon the outer and fortuitously adhering sheet. The forces of friction and magnetism are not, however, so great as to interfere with the normal progress of the intended sheet over 100 ways 11.
- As particularly shown in Fig. II the magnetic roller may be made up of a plurality of sheet-engaging and separated sections, to which the numeral 51 is repeatedly and 105 particularly applied, and these sheet-engaging sections are preferably the magnetically active sections.
- Fig. II shows also that in the particular installation illustrated three conveyers are 110 arranged in a row together, and that the magnetic rollers of all three may be arranged and driven as a unit. Also a single air-blast pipe 49 may serve all. Also, three friction rollers 48 are shown, one for each 115 conveyor. Of course there might be a plurality of rollers 48 for one section, arranged on a common axis, or arranged to be engaged successively.
- Adjacent to and cooperating with the 120 magnetic roller 51 a series of bars 53 form a runway for sheets accidentally carried by the intended sheets and separated from adhesion to the intended sheets by the action of roller 51. This runway is conveniently 125 level surfaced and horizontally arranged, extending above the arched ways 11, spaced at a small interval from the ways at the crown of the arch, and extending on both sides beyond the point of approximate tangency. 130

On one side this runway extends adjacent to magnetic roller 51 and there forms with the surface of ways 11 a throat or gullet, narrowing in the direction of normal sheet 5 advance (anti-clockwise, Fig. I). It will be perceived that the sheet normally borne upon ways 11 enters this gullet and advances beneath runway 53 along its normal and intended course without interference, but 10 that a fortuitously adhering sheet, drawn aside and lifted by roller 51, advances above runway 53, and is by its own impetus, derived from adhesion to the sheet intended to be carried and by the added impetus given 15 by roller 51, advanced upon runway 53. Resting there, it may readily be picked up by an attendant and returned to the bosh 2.

But it will be observed that the separation is automatic, and takes place without disturbance of the proper and intended course 20 of the sheet immediately engaged by the suction cups.

The magnetic roller, power-driven, as has been said, is driven preferably at a surface 25 speed somewhat exceeding the speed at which the cup-bearing bell-crank lever 15 normally advances the sheets upon ways 11. It is of course desirable to give the separated sheet momentum to carry it forward 30 upon runway 53 but, apart from that, a difference in speed and, as preferably will be the case, an excess in speed in this particular is disruptive in its effect, tending to break 35 and assisting in the breaking of the adhesions, in consequence of which a double may have been lifted from the bosh.

It will be perceived that the force of magnetism alone, being exerted upon the nearer sheet more powerfully than the sheet more 40 remote, will, tend to effect separation. It will be apparent that roller rotation co-operating with magnetism will increasingly tend to effect separation. But, additionally, the differential speed of roller 51 already 45 spoken of has a disrupting effect which, co-operating with magnetism, tends to effect separation.

It will also be perceived (and this is mentioned in the specification of my patent 50 named above) that the bending of the sheet upon the arched face of ways 11, itself tends to break adhesions. Particularly the forward edges of doubles when so bent upon the ways tend to separate. Such being the case, 55 the runway 53 arranged as has been specified may itself be effective, without the co-operation of roller 51, to effect the stripping of the adhering sheet from the sheet intended to be carried. Or, if rotation be taken away, 60 and the roller 51 be left to serve as a magnet merely, this stationary magnet, properly spaced from ways 11 and properly positioned with respect to the edge of runway 53, will cooperate with the rack to strip away 65 the fortuitously adhering sheet. In these in-

stances just indicated, the roller being absent, or if, present, being stationary and constituting nothing more than a stationary magnet, it is the impetus imparted to the adhering sheet through the sheet to which it 70 adheres which is effective to accomplish stripping.

It will be perceived that by forming the magnetic roller 51 in sections, as I show and describe it, spaces are left between the 75 sections, and in these spaces the sheet-moving instrumentalities may have free access to the rear edges of the sheet.

I provide retaining bars 54 arranged concentrically with the adjacent ways and 80 spaced at an interval from said ways and properly arranged with respect to the sheet-advancing means, to the end that, as the sheet at its forward edge approaches runway 53 it will be held rearwardly by bars 85 54 to approximate conformity to the arched shape of the ways. This provision not only positions the rear edge of the sheet for engagement by pushers, but it increases and makes sure a bowing of the sheet, such as 90 to tend more certainly to break adhesions, and release doubles.

I claim as my invention:

1. In conveying apparatus for sheet metal of magnetic character the combination with 105 arched ways and means for advancing a sheet thereon, a runway extending to one side of the pathway of material upon said arched ways and at its receiving edge spaced at an interval from said arched ways, and a magnet arranged adjacent to and at an interval from said arched ways and adjacent the receiving edge of said runway.

2. In conveying apparatus for sheet metal of magnetic character the combination with 110 arched ways and means for advancing a sheet of metal thereon, a runway extending to one side of the pathway of material upon said arched ways and at its receiving edge spaced at an interval from said arched ways, and a rotatable magnetic roller arranged adjacent to and at an interval from said arched ways and adjacent the receiving edge of said runway, and means for rotating said magnetic roller.

3. In conveying apparatus for conveying sheet metal of magnetic character means for causing a sheet to advance along a fixed pathway and a rotating magnetic roller extending athwart the pathway and rotating 115 at a surface speed different from the speed of sheet advance as determined by the means first named.

4. The method herein described of separating adhering sheets of magnetic material which consists in subjecting the adhering sheets on one side to one propelling impulse and on the other side to the influence of a magnetic roller turning at a surface speed different from the speed of 120 125 130

advance imparted by the propelling impulse first named.

5. In conveying apparatus for sheet metal the combination of arched ways and means 5 for advancing a sheet upon said ways in conformity to the arched shape thereof, and a friction disk adapted to bear upon the surface of a double advancing upon said ways and exert upon the member of the double 10 immediately engaged resistance to advance upon said ways.

6. In conveying apparatus for sheet metal the combination with upwardly rising arched ways, means for causing sheets to 15 advance upon said ways in conformity to the arched shape thereof, an idle roller of

elastic material adapted to engage the surface of a double fortuitously advancing on said ways, a positively driven magnetic roller spaced at an interval from the path of a sheet upon said ways and at a point in the extent of the path beyond said elastic roller, and a runway adapted to receive the undesired member of a double separated by the action of said magnetic roller. 20 25

In testimony whereof I have hereunto set my hand.

JOHN W. FREE.
